CLAIM

The ornamental design for an auxiliary power outlet plug-in charger, as shown and described.

DESCRIPTION

FIG. 1 is a front perspective view showing an auxiliary power outlet plug-in charger of the present invention;

FIG. 2 is a rear perspective view thereof;

FIG. 3 is a top view thereof;

FIG. 4 is a left side view thereof;

FIG. 5 is a right side view thereof;

FIG. 6 is a bottom view thereof;

FIG. 7 is front view thereof; and,

FIG. 8 is a rear view thereof.

In the drawings, the broken line showings are for purposes of illustrating environmental structure or portions of the auxiliary power outlet plug-in charger that form no part of the claimed design.

1 Claim, 3 Drawing Sheets
